UNITED STATES PATENT OFFICE.

MICHAEL F. DEININGER, OF BROOKLYN, NEW YORK, ASSIGNOR OF ONE-HALF TO JOHN H. WALTERS, OF BROOKLYN, NEW YORK.

ALARM FOR CATCH-BASINS.

933,237.

Specification of Letters Patent. Patented Sept. 7, 1909.

Application filed December 26, 1908. Serial No. 469,327.

To all whom it may concern:

Be it known that I, MICHAEL F. DEININGER, a citizen of the United States, residing at Brooklyn, in the county of Kings and State of New York, have invented an Improvement in Alarms for Catch-Basins, of which the following is a specification.

The primary object of my invention is to provide an attachment for a pan or receptacle which will sound an alarm when the water or other fluid entering said pan or receptacle reaches a predetermined level; the present device being especially adapted for application to the drip-pan of a conventional ice-chest or refrigerator, to give an audible alarm when the drip-pan is full or nearly so, and therefore requires emptying. This is accomplished in the present instance by the employment of an ordinary form of 15 spring-actuated bell and float for operating the trip-lever thereof, in connection with a peculiar form of clip device for attaching the bell and its trip-lever to the upper edge of the pan; all as hereinafter particularly 20 described, and specifically set forth in the appended claims.

In the accompanying drawings, which form a part of this specification: Figure 1 is a view showing the application of the device 30 to a pan. Fig. 2 is a detail plan view, illustrating the manner of forming the clip device from sheet metal. Fig. 3 is an enlarged side elevation of the clip, with the bell and operating-lever connected thereto. Fig. 4 is a side elevation, showing a slight modification 35 in the construction of the clip.

Like numerals of reference indicate like parts in all the figures of the drawings.

In carrying out my invention I employ in 40 the first instance a well-known form of spring-actuated bell, 5, a part, as 6, of which is provided at its outer end with a depression 7, for the purpose hereinafter explained. The trip-lever 8 of this bell is extended a 45 suitable distance, and upon the outer end thereof is secured a float 9.

For the purpose of readily and conveniently applying this bell and its operating 50 or trip-lever in connection with a drip-pan or receptacle receiving water or other fluid, I provide a clip device which is made up of sheet metal, preferably spring metal, in such manner as to firmly grip the bell, pivotally support the trip-lever thereof, and 55 detachably engage the upper edge of the pan

or receptacle. In forming this clip I employ a metal strip having lateral members 10, 10, pivot-ears 11, 11, struck upwardly therefrom at one side of the aforesaid members, and a lip 12 cut from the body portion of the strip at the other side of the lateral members, the extremity of this end of the strip being formed with a boss 13. The strip is bent upon itself in opposite directions to form a loop 14 and a spring hook 15, the pivot-ears being located at the upper end of the combined loop and hook, while the spring members 10 and lip 12 are carried by the loop portion thereof. The loop 14 is adapted to receive the bell 5 within the same, and the outer ends of the members 10 are bent to provide spring fingers which embrace the opposite sides of said bell to hold it in place; but in order to form a more secure engagement of the clip device with the bell the lip 12 is bent to yieldingly engage the lower end of the bell, while the outer spring member of the loop presses against the front of the same with the boss 13 in engagement with the depression 7. When 80 the bell is slipped into the loop to be engaged in the manner hereinbefore described, the operating-lever of the bell is pivotally connected to the ears 11 by means of a pin 16. In this manner, as will be seen, the bell and its operating lever carrying the float are firmly connected to the clip device, and the parts are thereby adapted to be supported at the upper edge of the drip-pan by simply passing the spring hook over said 85 upper edge, which will locate the bell at the outer side of the pan and the float within the same, as shown in Fig. 1 of the drawings.

The operation of the alarm will be readily understood, for when the water in the pan reaches a certain level it will raise the float, and the latter being attached to the trip or operating lever will operate the latter to release the mechanism of the bell, causing an alarm to be sounded, so that any one within 90 hearing of the alarm will know that the pan 100 is full and should be emptied.

In Fig. 4 I have shown a slight modification of the invention, in which the support for the bell consists of a vertical member 17 having a forwardly-projecting lip 19 at its lower end and the engaging spring fingers 10 at an intermediate portion of said vertical member; this support for the bell being similar to the other hereinbefore described, with 110

the exception of the omission of the forwardly projecting spring member of the loop. In this modification the bell is supported by engaging the spring members or 5 fingers 10 and the lip 19, in connection with the pivotal engagement of the operating lever with the pivot-ears 11.

Having described my invention, I claim:

1. In an alarm device for the purpose set forth, the combination with a spring-actuated bell and its trip-lever, the latter having a float at its outer end and the bell having a depression in the front of the same, of a clip device comprising a combined spring hook 10 and loop, the latter being adapted to receive the bell and provided with opposite spring fingers engaging the sides of the bell and an upturned free member with a boss at its outer end engaging in the depression in 15 the front of the bell, and pivot-ears at the upper end of the clip device between which the trip-lever is pivoted, substantially as shown and described.
- 20

2. In an alarm device for the purpose set forth, the combination with a spring-actuated bell and its trip-lever, the latter having a float at its outer end and the bell having a depression in the front of the same, of a clip device comprising a combined spring hook and loop, the latter being adapted to receive the bell and provided with opposite 25 spring fingers engaging the sides of the bell, a lip engaging the lower end of the bell, and a forwardly-projecting spring member with a boss at its outer end engaging in the depression in the front of the bell; together with pivot-ears at the upper end of the clip device between which the trip-lever is pivoted, substantially as shown and described.

In testimony whereof I have signed my 40 name to this specification in the presence of two subscribing witnesses.

MICHAEL F. DEININGER.
